UNITED STATES PATENT OFFICE.

CHARLES W. STIMSON, OF NEW YORK, N. Y.

STOCKING-SUPPORTER.

SPECIFICATION forming part of Letters Patent No. 793,241, dated June 27, 1905.

Application filed May 14, 1904. Serial No. 207,905.

To all whom it may concern:

Be it known that I, CHARLES W. STIMSON, a citizen of the United States, residing in the city, county, and State of New York, have invented certain new and useful Improvements in Stocking-Supporters; and I do hereby declare the following to be a full, clear, and exact description of the invention, such as will enable others skilled in the art to which it applies to make and use the same.

My invention relates to improvements in stocking-supporters; and it consists in a novel arrangement of stocking-supporting tapes whereby the abdomen of the wearer is repressed and supported in an easy and natural manner and without injurious action and whereby the stocking-supporter is rendered easy of adjustment and is permitted to conform readily to the movements of the individual wearer.

The objects of my invention are to give to the wearer an erect carriage and a graceful figure, to avoid all injurious action, to both repress and support the abdomen, to render the stocking-supporter easily adjustable to persons of different figures, to permit the stocking-supporter to conform readily to the movements of the wearer, and to make the stocking-supporter simple, compact, and relatively inexpensive.

I will now proceed to describe my invention with reference to the accompanying drawings and will then point out the novel features in claims.

In the said drawings, Figure 1 shows a front view of one form of my improved stocking-supporter applied to a conventional female figure, and Fig. 2 is a detail view illustrating an alternative feature of construction thereof.

My improved stocking-supporter comprises a waist-piece 1, which is usually a belt provided with the usual buckle 2 to permit adjustment and facilitate the application of the stocking-supporter. To the front portion of this belt 1 are secured, on opposite sides of the center line and well around toward the sides of the wearer, tapes 3, adapted to extend obliquely downward and to be secured each to a stocking on the opposite leg of the wearer.

Other tapes 4 are secured to the belt 1 be-

tween the points of attachment of tapes 3, and these tapes 4 are adapted to hang directly downward, or nearly so, and to be secured each to the stocking on the corresponding leg of the wearer. While the tapes 3 may be 55 stitched together at their point of intersection, as shown in Fig. 2, I prefer not to do so, but to leave them free for adjustment. Similarly I prefer not to connect tapes 4 and 3 where they cross.

Heretofore it has been old to employ in stocking-supporters a front pad supported by a waist-belt or by attachment to a corset, from which pad hang stocking-supporting tapes. The pull of these tapes on the pad is substantially directly downward or downward and to the sides. The pressure produced by the pads of such devices on the abdomen is therefore in the main downward and to some extent inward, and such pressure is exerted very close 70 to the median line. It is well known that excessive pressure along the median line, and especially downward pressure, is injurious and should be avoided. Moreover, pressure applied along the median line tends to produce 75 bulging of the abdomen at the sides. A more natural and effective way of repressing the abdomen is to support it from beneath and at the same time press it in. This is accomplished by my improved stocking-supporter, 80 since the tapes 3, lying as they do beneath the curve of the abdomen, act to support the same and also to repress it. This inward and upward pressure so exerted is not injurious, but, to the contrary, is beneficial. Furthermore, relatively little pressure is applied along the median line, most of the pressure being applied at the sides, and this effectually prevents bulging of the abdomen at the sides.

As used normally, the front portion of the 90 waist-belt 1 of my stocking-supporter will be just below the lower edge of the corset when one is worn, and the tapes 3, which will ordinarily be fastened to the stockings well around toward the outside of the leg, will then be 95 substantially parallel to the lines of the groins and to the fibers of the external oblique muscles by which the abdomen is mainly supported. The action of the tapes 3 is therefore entirely in harmony with that of the 100

muscles. The vertical tapes 4 act mainly to support the stocking, but likewise have repressive action. Being substantially parallel to the rectus muscle, they give at the sides of 5 that muscle substantially the same support which that muscle gives the abdomen at the center.

The action of the tapes 3 may be varied to adjust the stocking-supporter to different figures by shifting the points of attachment of 10 said tapes to the stocking to one side or the other, and, if desired, one of the tapes 3 may be fastened to the stocking toward the inside 15 of the leg and the other well around to the outside of the other leg, and thereby the action of the stocking-supporter will be varied so that the pressure will be exerted to one side 20 of the median line instead of at the center. This is often desirable when one portion of the abdominal wall is weak, as after hernia or 25 a surgical operation or when the wearer has a tumor.

It is obvious that my invention is susceptible 25 to many variations and modifications, and I do not limit myself to the particular construction of the stocking - supporter or the 30 particular arrangement of tapes herein illustrated and described.

What I claim is—

30 1. In a stocking-supporter, the combination with a front waistband having means for

supporting same on the person of a wearer, of intermediate stocking - supporting tapes depending therefrom, and longer diagonal stocking-supporting tapes likewise secured to said 35 band and extending from their points of attachment thereto across to the opposite side of the wearer.

2. In a stocking-supporter, the combination with a front waistband having means for 40 supporting same on the person of a wearer, of intermediate stocking - supporting tapes depending therefrom, and longer diagonal stocking-supporting tapes likewise secured to said 45 band and crossing each other below the same.

3. In a stocking-supporter, the combination with a front waistband having means for supporting same on the person of a wearer, of diagonal stocking - supporting tapes secured thereto, and intermediate stocking-supporting 50 tapes likewise secured to said waistband but arranged to hang more directly downward and crossing said diagonal tapes, said intermediate tapes each secured to a diagonal tape at its point of intersection therewith.

In testimony whereof I affix my signature in the presence of two witnesses.

CHARLES W. STIMSON.
